UNITED STATES PATENT OFFICE

152,985

DESIGN FOR A REFRIGERATOR CABINET

Theodore H. Koeber, Oak Park, Ill., assignor to
International Harvester Company, a corpora-
tion of New Jersey

Application April 12, 1947, Serial No. 138,337

Term of patent 7 years

(Cl. D67—3)

To all whom it may concern:

Be it known that I, Theodore H. Koeber, a citizen of the United States, residing at Oak Park, in the county of Cook and State of Illinois, have invented a new, original, and ornamental Design for Refrigerator Cabinet, of which the following is a specification, reference being had to the accompanying drawings, forming part thereof, in which:

Figure 1 is a perspective view taken from one side of a refrigerator cabinet showing my new design;

Figure 2 is a perspective view taken from the other side thereof; and

Figure 3 is a fragmentary top plan view of a front portion of the cabinet and showing the relationship between the door and door handle.

I claim:

The ornamental design for a refrigerator cabinet, as shown.

THEODORE H. KOEBER.
